UNITED STATES PATENT OFFICE.

EMILE LACROIX AND CHARLES J. CRERAN, OF HOLYOKE, MASSACHUSETTS.

OIL PUMPING AND DISTRIBUTING APPARATUS.

SPECIFICATION forming part of Letters Patent No. 791,427, dated May 30, 1905.

Application filed April 25, 1904. Serial No. 204,764.

To all whom it may concern:

Be it known that we, EMILE LACROIX and CHARLES J. CRERAN, citizens of the United States of America, and residents of Holyoke, 5 in the county of Hampden and State of Massachusetts, have invented certain new and useful Improvements in Oil Pumping and Distributing Apparatus, of which the following is a full, clear, and exact description.

10 This invention relates to improvements in an apparatus for pumping oil from one or more supply-tanks into one or more distributing-tanks, each of which latter tanks has leading therefrom pipes for conveying and 15 delivering the oil to differently-located bearings or places where a continuous lubrication or oiling is desirable or necessary, the apparatus having provision for a return back to the supply tank or tanks of any excess of oil 20 which may be pumped into the distributing tank or tanks.

The object of the invention is to generally improve and increase the efficiency of the pumping apparatus and render it most satisfactorily available for its demands in use.

The invention consists in combinations and arrangements of parts and constructions of certain of the parts, all substantially as hereinafter described, and set forth in the claims.

30 The apparatus may be organized with a single oil-supply receiver and a single distributing-tank, or it may be made duplex, with double oil-supply and oil-distributing tanks and conjunctive appliances, a single actuating mechanism being provided in common to and serving for both departments of the apparatus.

In the drawings, Figure 1 is a perspective view showing the oil-distributing apparatus 40 duplex. Fig. 2 is substantially a sectional view vertically and centrally through the principal portions of a single department of the pumping apparatus. Fig. 3 is a plan view of part of the same. Fig. 4 is a perspective view of an interchangeable cam included in the mechanism. Fig. 5 is a sectional view of a needle-valve provided in one of the distributing-pipes leading to a bearing to which oil is to be delivered.

Similar characters of reference indicate corresponding parts in all of the views.

Describing the apparatus regarded as a single-acting oil-distributing pump and referring to the drawings, A represents an oil-supply tank, the same having a removable cover a^1 therefor and having in its top a strainer a^2 . Below the oil-supply tank is a body B, having, by reason of the cylindrical opening therein and the continuation in the coupled section b , a cylindrical pumping-chamber J, down 55 to the top of which leads a vertical oil-pipe C from the bottom of the oil-tank, said pipe having a shut-off or regulating cock D, having an operating-handle c therefor. Opposite the coupled section b and aligned therewith is a section d , coupled to the body B, having a stuffing-box d^2 at its end and through which and into the cylindrical chamber plays a round plunger-bar or piston E, having at its outer end a roller e to receive the impingement thereagainst of the 60 operating-cam F on a cam-shaft G, which is mounted for rotation horizontally at right angles to the length of the piston E. The piston E is provided with a cross-bar E^2 , to which are connected rods f^2 , which play 65 through holes f^3 , formed horizontally and parallel with the piston through the extensions B^2 of the chamber including body B. The spiral springs f encircle the rods f^2 and are 70 in compression between the cross-bar E^2 and the parts B^2 of the cylinder-body and retract the piston after each working movement by the cam. The extremities of the rods f^2 , which 75 project through and beyond the holes f^3 , are screw-threaded, as indicated at f^4 , and receive 80 thumb-nuts f^5 , which constitute adjustable stops, so that the piston may not move in the 85 opposite direction from its cam-thrust movement in any undesirable degree.

Located above the cylinder-chamber J is an 90 oil-distributing tank H, into the bottom of which is connected a vertical pipe g, which, by elbow-coupling g^2 , is coupled to the section b , comprised in which is a portion of the cylinder-chamber J, a check-valve g^3 being 95 provided in the bottom of the distributing-chamber at the junction therewith of the pipe g, and a further check-valve g^4 is preferably

provided in the vertical pipe g . The reciprocatory movement of the piston E insures a forcing of the oil conveyed into the pumping cylindrical chamber J from the oil-supply tank A through the conduit g up into the distributing-tank H past the check valve or valves, and the means for imparting the rotary movement to the cam for actuating the pumping-piston E will be now described. The cam, which may be of any suitable shape, (a variety of shapes being noticed in comparison of Figs. 1, 2, and 4,) is mounted on the aforementioned horizontal shaft G , which is supported in suitable journal-bearings h in working proximity to the roll-ended piston, and said shaft has affixed thereon a disk or wheel L , which, as shown in Fig. 1, is provided with internal ratchet-teeth i .

M represents a pawl-carrier carried by the hub k , which is loose about the extremity of the cam-shaft G , said carrier in the drawings being shown as an arm or rod radially extending from the hub in an upward inclined direction adjacent the face of the ratchet-wheel and to a block m , affixed by the set-screw m^2 to the pawl-carrying rod m . The pawl o is understood as being pivotally joined, and o^2 represents the pawl-spring.

N represents a driving-shaft revolvably carrying the crank-pin n , to which one end of the pitman-rod O has connection, the other end of the pitman-rod having an appliance p , including integral or joined double sleeves, with perforations at right angles, one sleeve-like portion encircling and being fastened to the pitman-rod, while the other encircles and is adjustably fastened to the pawl-carrier rod M by the set-screw p^2 . By loosening the screw and sliding the sleeve-like part of the appliance p up or down the stroke of the pitman will impart a varied swinging movement to the pawl-carrier for a correspondingly greater or less partial rotary movement to the ratchet-wheel on the cam-shaft.

Q represents a click or detent engaging in the ratchet-teeth and for preventing retrograde movement of the wheel L . Said detent is pivotally mounted on a stationary bracket q and has the pawl-spring g^2 for keeping it in its ratchet-tooth engagement.

In order to vary the impulses or pumping action of the pumping-piston, interchangeable cams of different shapes may be detachably affixed on the cam-shaft, it being only necessary to remove the journal-caps and lift the shaft from one end thereof to permit of the removal of one cam and the replacement of another.

The cams G , of whatever form they may have, are provided with oppositely-extended tapered hubs s , split from their ends longitudinally, as indicated at s^2 , and rendered contractible and also externally screw-threaded, as at s^3 , at their end portions to receive there-

on the internally-threaded nuts t , which are shown as having flanges t^2 for convenience of hand operation. The cam being slipped on the shaft and adjusted, (the cam and its hubs being understood as having a bore from end to end,) the hand-nuts are tightened on the tapered and screw-threaded extremities of the split hubs, binding the latter and the cam securely on the shaft.

The ratchet-wheel L , as indicated in Figs. 1 and 3, may have in addition to the internal ratchet-teeth the edgewise-located ratchet-teeth u in a wider circle of arrangement than that of the ratchet-teeth i and pawl o^1 , properly carried on the pawl-carrying arm M , and, as represented in Fig. 3, may engage the set of ratchet-teeth u .

v represent oil delivery or distributing pipes radiating from the more or less elevated distributing-tank H and understood as extending to variously-located bearings or places where oil or lubrication is required, and in Fig. 1 one of the pipes v is shown as going to a journal-bearing x in a manner to supply lubrication thereto, said pipe v having a needle-valve w coupled therein, so that the quantity of oil to be delivered from the distributing-pipe v may be minute or considerable, according to the adjustment of the needle-valve.

Connected with the top of the distributing-tank H is a conduit P , serving as an overflow-pipe and extended back to connection with the supply-tank A , the said overflow-pipe having appertaining thereto the check-valve y , properly fitted in the coupling y^2 , which connects different sections of the overflow-pipe P . Said check-valve is held closed to the seat by the spiral spring y^3 , one end of which is in bearing against the valve, while the other end of such spring is in bearing against a screw-plug y^4 , which has a thread engagement within the upper end of the coupling y . By turning the screw-plug the spring compression on the valve may be varied, and consequently there may be acquired a regulation of the pressure at which the excess oil in the distributing-tank would be forced past the check-valve and returned to the supply-tank.

In Fig. 1 a duplication of the oil and distributing tanks A and H is illustrated with the appertaining additional pumping mechanism, and conduits similar to those described in respect of the left-hand department of the apparatus are seen in said view, Fig. 1. The pumping-piston E for the duplicated pumping arrangements is shown as aligned with the pumping-piston E of the first-contemplated pumping apparatus, but at the opposite side of the cam G , but to receive similarly its impulses therefrom, and it is unnecessary to describe in detail the duplicated parts of the apparatus, which are substantially identical with those already pointed out for the one department of the machine, although it is per-

tinent to state, as clearly seen from the illustration, that one cam and cam-actuating mechanism is combined in common to both of the duplicated pumping apparatuses and serves 5 the double duty of operating both thereof. The cam-shaft is shown in Fig. 1 as having a wheel ω with a hand-crank, by means of which the pumping apparatus may be operated by hand in case power is not available or it is 10 not desirable to run the pump for a long time by power.

Various changes in minor details and proportions of the parts may be made without departing from our invention.

15 Having thus described our invention, what we claim, and desire to secure by Letters Patent, is—

1. In an oil-pumping apparatus, in combination, an oil-supply tank, a cylinder below 20 and pipe-connected therewith, a piston in said cylinder, and means for imparting reciprocatory movement thereto, a distributing-tank located above the cylinder and pipe-connected therewith, and having one or more oil-distrib- 25 uting conduits leading therefrom, and an over-flow-pipe leading from the distributing-tank back to the supply-tank.

2. In an oil-pumping apparatus, in combination, an oil-supply tank, a cylinder below 30 and pipe-connected therewith, a piston in said cylinder, and means for imparting reciprocatory movement thereto, a distributing-tank located above the cylinder and pipe-connected therewith, and having one or more oil-distrib- 35 uting conduits leading therefrom, and an over-flow-pipe leading from the distributing-tank back to the supply-tank.

back to the supply-tank and a yielding valve therein.

3. In an oil-pumping apparatus, in combination, an oil-supply tank, a cylinder below 40 and pipe-connected therewith, a piston in said cylinder, and means for imparting reciprocatory movement thereto, a distributing-tank located above the cylinder and pipe-connected therewith, and having one or more oil-distrib- 45 uting conduits leading therefrom, and an over-flow-pipe leading from the distributing-tank back to the supply-tank, a spring-closed valve therein, and means for adjusting the compression of the spring for such valve. 50

4. In an oil-pumping apparatus, in combination, an oil-supply tank, a cylinder below 55 and pipe-connected therewith, a piston in said cylinder, and means for imparting reciprocatory movement thereto, a distributing-tank located above the cylinder and pipe-connected therewith, and having one or more oil-distributing conduits leading therefrom, and an over-flow-pipe leading from the top of the distributing-tank back to the supply-tank, a check- 60 valve in said overflow-pipe, a spring applied for a closing pressure to said valve, and a screw-plug adjustably operable against the said spring.

Signed by us at Springfield, Massachusetts, 65 in presence of two subscribing witnesses.
